Edward F. Robinson, of Boston, Mass.
Letters Patent No. 566. Dated May 10th 1853,

The schedule referred to in these Letters Patent and making part of the same

To all persons to whom these presents shall come,

Be it known that I, Edward F. Robinson, of Boston, in the County of Suffolk, and State of Massachusetts, have invented or produced a new and ornamental design for Cooking Stoves, and I do hereby declare that the same is fully represented in the accompanying drawings of which

Des. 566

The design on each door consists of an elongated flower, or elliptical rosette G, (see Figure 2) composed of a series of un serrated leaves, radiating from a central projection or button b, and imposed on a series of concave grooved rays c, c, c, &c, interrupted with convex grooved rays d, d, d, &c. The vertical corners are curved quadrated as seen at, a, a, in Figure 3. The mouldings of the base are composed of a fillet, f, a scotia, g, a torus or bead, h, an ovollo, i, a fillet, k, and a cavetto, l.

The cornice mouldings are an ovollo, m, a fillet n, and a cavetto o, surmounted by a bead p. The ornamental character of the remainder of the design will be clearly understood by designers or stove pattern makers on inspection of the drawings.

The words, "Boston Jewell - N°. 8", as seen in Figure 1, constitute no part of the said design.

What is claimed is the ornamental configuration or design as exhibited in the accompanying drawings.

In testimony whereof I have hereto set my signature this Fourteenth day of March AD, 1853.
